PROCESS AND APPARATUS FOR THE
TREATMENT OF RAYON PACKAGESPeter P. Kriek, Enka, N. C., assignor to American
Enka Corporation, Enka, N. C., a corporation of
Delaware

Application May 18, 1938, Serial No. 208,672

7 Claims. (Cl. 242—130)

This invention relates to expanding mechanism for use in the handling of thread or yarn packages and to a process in which expanding mechanism is utilized. More particularly the invention is directed to an apparatus adapted for use in the insertion of a support in normally unsupported dry packages of artificial silk subsequent to the winding-off or twisting operation. In the manufacture and treatment of artificial silk in package form, it is quite common to subject internally unsupported wound packages of yarn to an "after treatment" which may include final washing and subsequent drying of the unsupported packages. In order to effect uniform shrinkage of the yarn throughout the package, it is usually desirable to also deform the same prior to final drying; but the deforming step tends to collapse and tangle the inner convolutions of yarn. The present invention is well adapted for expanding, reforming and inserting supports for such previously deformed packages. Regardless of whether the deforming step is employed, when the packages are dried, the inner convolutions of yarn have a tendency to fall and become entangled. Because of this and other objectionable characteristics of dried internally unsupported yarn packages, the handling of such packages after the drying operation is both difficult and inefficient. In view of the somewhat loose and entangled condition in which the yarn forming the inner convolutions of many of the packages is left after the drying operation, difficulties are often experienced in providing the packages with internal supports or bobbins such as are utilized in rewinding or coning operations.

Aside from the desirability of internally supporting the yarn packages during the coning period, the need for providing each of the packages with an internal support is present during transportation of the same within the manufacturing plant, as the jolting and jarring to which the dry packages are subjected during transportation is such that the relatively loose inner convolutions of yarn are further distorted and disarranged.

To obviate the difficulty heretofore encountered, it is proposed by this invention to provide a means for and a process by which a support may be inserted within a preferably deformed, normally internally unsupported yarn package subsequent to the drying thereof in a manner to avoid a displacement of the inner convolutions of yarn. This invention contemplates a method and apparatus by which an expandible support

may be inserted within an artificial silk package in contact with the inner convolutions of yarn for the purpose of maintaining the latter in position.

It is another object of this invention to provide a process which involves the extension of the thread-free interior of a dry package of yarn to permit the insertion therein of a rolled support member and the expansion of the rolled support in a manner to urge loose convolutions of yarn outwardly and thereby to avoid undesirable slack therein. The invention further contemplates the provision of mechanical expanding apparatus to extend the thread-free interior of respective packages, which apparatus permits the insertion of a support member within a package in such a manner that the support may be retained within the package while the expander is removed, whereupon the expander may be utilized to again extend the interior of the package and cause the support to assume a position more closely adjacent the inner convolutions of yarn.

A further specific object of the invention is to reform into a round shape an artificial silk package that has been deformed in a previous stage of processing for the purpose of eliminating shrinkage variations in the finished yarn. In such a case the size of the opening in the center of the package is considerably reduced from what it was when the package was first wound and it is desirable that this opening be restored to its original size as much as possible. The apparatus described below is well adapted to this reopening of the deformed or collapsed package.

Further objects and advantages of the invention will be apparent from a consideration of the following detailed description when considered in connection with the accompanying drawings wherein:

Figure 1 is a front elevation of an expanding apparatus constructed in accordance with this invention;

Figure 2 is a top plan view of the apparatus shown in Figure 1;

Figure 3 is an end view of a deformed unsupported package with an expanding means shown therein in retracted position;

Figure 4 is an end view of a package of yarn with the means therein radially expanded and surrounding a rolled support;

Figure 5 is a sectional view taken along line 5—5 of Figure 4;

Figure 6 is a sectional view of the package with

a support therein in operative relation after the completion of one expanding operation;

Figure 7 is a sectional view showing the package and apparatus at the beginning of the second expansion with the package, preferably in inverted position;

Figure 8 is a view similar to Figure 7 with the package and apparatus in the position attained at the completion of the second expansion; and
10 Figure 9 is an end view of the package in the form attained after subjection to two expansion operations.

Referring now to the drawings in detail and especially to Figures 3-9 inclusive in which the 15 various steps of the process constituting a part of this invention are shown, in Figure 3 the numeral 10 designates a wound artificial silk package which has been deformed either prior to, or during the drying operation with the result 20 that the convolutions of yarn defining the area of its thread-free interior are substantially collapsed in a soft and fluffy condition. Positioned within this thread-free interior are a series of 25 movable fingers 11 extending up through its central hollow portion, said fingers being adapted to move radially and force outwardly the inner convolutions of yarn. In Figure 3 these fingers are shown in retracted position, and their upper ends substantially come together. In Figure 4 the fingers 30 11 are shown in radially expanded position in vertically parallel relationship. Within the circle described by said fingers there is positioned a coiled support 12 which may be of fiber board or other material of sufficient stiffness and resiliency to uncoil itself and thus frictionally engage 35 the yarn between the fingers 11. In Figures 5 and 6 the packages are shown after the described expansion operation has been completed. Figure 5 shows the package and support while still on 40 the expanding apparatus, and Figure 6 after the package and support have been removed from the fingers 11. In this condition the packages supported by the fibrous support member 12 have assumed their unrolled position permitted by the 45 removal of the fingers and the resistance offered by the yarn.

Following the initial expansion of the package as shown in Figures 3-6 inclusive, the package and support may be inverted and again placed 50 over the fingers 11 as shown in Figure 7 for a further expansion operation. In this further expansion operation, however, the support 12 and the hollow portion of package 10 both surround the fingers 11 and consequently upon radial 55 expansion of the latter, the fiber support 12 will be more firmly pressed against the inner convolutions of the yarn of package 10. The position of the support and the interior contour of the package after the second expansion are shown 60 in section in Figure 8 and in plan in Figure 9.

It will be noted that at the termination of the first expansion of the fingers 11 as shown in Figure 4, the interior of the package is substantially cylindrical, but may be given slightly the contour of the frustum of a cone. This is because of the positioning of the fulcrum of the fingers 11 together with the more or less inherent flexibility of the fingers as will hereinafter more fully appear. By inverting the package and subjecting 70 the same to the second expansion, the pressure will be such that the thread-free interior of the package 10 will assume a more exactly cylindrical contour.

It will be clear that the inner convolutions of 75 yarn in the packages as shown in Figure 6 and

particularly in Figure 9 are extended in a manner similar to that had after the initial winding operation and therefore during the coning operation the yarn is wound off without entanglement and incident rupture even throughout the 5 inner convolutions of yarn.

The apparatus used in carrying out the process heretofore described is shown in its preferred form in Figures 1 and 2. Fingers 11 which constitute the expanding means positioned within 10 the thread-free interior of the yarn package in carrying out the process are supported on an annular plate 13 which also acts as a fulcrum and which is suitably fastened at 14 to the cylinder 15 of a fluid operated telescope type jack 16 which is provided with a base 17 resting on a support 18 which support 18 is a cross member running between the legs 19 of table 20. Table 20 is provided with a top 21 which has a central recess at 22 through which the fingers 11 extend. Radially positioned around the annular opening 22 are a series of adjustable set screws 23 which support a spider 24 which in turn supports the lower surface of the package during the expanding treatment heretofore described. Beneath the 20 top of the table 20 and between the same and the annular support plate 13, there are a series of toggle links 25 suitably fastened to the fingers 11 which are operatively connected to the innermost piston 26 of jack 16, thus when jack 16 is 30 extended in response to fluid pressure, piston 26 actuates toggle links 25 which in turn radially expand fingers 11, and when pressure is released from jack 16 piston 26 falls in response to gravity and fingers 11 are retracted. To control the 35 operation of jack 16, there is provided a two-way valve 27 which selectively permits fluid to flow into jack 16 through conduit 28 and permits exhaust therefrom through conduit 29. Valve 27 is controlled by a single throw lever 30 operably connected at 31 to a treadle 32.

As is clearly shown in Figure 2, spider 24 not only acts to support package 10 but also functions as a guide for fingers 11 as they are subjected to radial movement and may be used to lift off 45 the package after the expansion is completed. The dotted lines indicate the position of the fingers when retracted and the solid lines the location thereof in extended position.

In carrying out the process of the present invention by utilizing the apparatus above described, the unsupported package is placed over the upstanding fingers 11 until its lower edge comes to rest on spider 24 and the fingers are moved radially outwardly. Thereafter, coiled 50 support 12 is inserted within the cylinder defined by the upstanding fingers 11. At the time coiled support 12 is placed in this position, it is biased to a point such that it will seek to unroll itself. Thus, it is that coiled support 12 in an effort 60 to become unbiased will unwind and abut the inner convolutions of thread between the fingers 11.

This completes the first expansion, and at this time the thread-free central portion of package 10 is generally cylindrical in contour. The package 65 10 is then lifted off the machinery. Since the fingers 11 are no longer in engagement with the inner convolutions of the thread, the coiled support 12 continues to become unbiased and in so doing, more closely engages the inner convolutions of thread which define the generally 70 thread-free interior of the yarn package 10.

At this point, it will be seen that the previously unsupported package is supported by a relatively 75 stiff cone of fiber board or other suitable material

and is in condition for transportation. However, due to the particular positioning of the fulcrum of the levers constituting fingers 11 and the positioning of the toggles 25 thereon together with the generally inherent flexibility of fingers 11 the inner contour of the now supported package may be slightly frustro conical. Should it be desired to obviate this condition and to insure an even better placement of the coiled support 12 against the inner convolutions of thread of package 10, the package may be inverted and again placed over fingers 11, the latter being in a retracted position. When these fingers are thereafter again expanded radially, the contour of the hollow portion of package 10 assumes a more exactly conical shape and the coiled support is even more firmly pressed against the inner convolutions of thread defining the central thread-free interior of the package.

20 During the course of the foregoing operation when it is desired to move the fingers 11 outwardly, pressure is applied to the treadle 32 which opens valve 27 permitting fluid under pressure from any suitable source to flow through conduit 25 and thus into jack 16 which will raise piston 26 to which toggle links 25 are connected and toggle links 25 will cause the fingers 11 to move. When pressure is released, piston 26 falls and the fingers assume their retracted position.

30 It is intended that the present application shall cover packages of artificial silk produced either by the bobbin process or the centrifugal bucket spinning method, as the instant process and apparatus are applicable to any type of package that 35 of necessity must be expanded for the insertion of an internal support.

What I claim is:

1. A process of preparing a deformed, dry, internally unsupported wound package of yarn for 40 handling conditions in which a support is required for efficient operation to prevent displacement and entanglement of the inner fluffy convolutions of yarn comprising reforming the inner convolutions of yarn by radially applying an extending force to the convolutions of yarn defining the thread-free interior of a wound yarn package, inserting a core within the thread-free interior of the package while said convolutions are extended to a size substantially equal to the normal round 45 circumference of the innermost convolutions of yarn, permitting an adjustment to take place between the core and the convolutions of yarn and then applying equalizing radial pressure within the core whereby the latter is given uniform diameter and the yarn convolutions assume normal 50 circumferences and are maintained substantially free of tangles during winding-off and other handling operations.

2. A process of preparing a dry internally unsupported wound package of yarn for handling 60 conditions in which a support is required for efficient operation to prevent displacement and entanglement of the inner fluffy convolutions of yarn comprising radially applying an extending force to the convolutions of yarn defining the thread free interior of a wound yarn package, inserting a rolled support biased outwardly within the thread free interior of the package while said 65 convolutions are extended to a size substantially equal to the normal circumference of the innermost convolutions of yarn, permitting an adjustment to take place between the rolled support and the convolutions of yarn and then applying 70 equalizing radial pressure within the core where-

by the latter is given a uniform diameter, and the yarn convolutions assume normal circumferences and are maintained substantially free of tangles during winding-off and other handling operations.

3. A process of preparing a dry internally unsupported wound package of yarn for handling 5 conditions in which a support is required for efficient operation to prevent displacement and entanglement of the inner fluffy convolutions of yarn comprising radially applying an extending 10 force to the convolutions of yarn defining the thread free interior of a wound yarn package, inserting a rolled support biased outwardly with the thread free interior of the package while said convolutions are extended to a size substantially 15 equal to the normal circumference of the innermost convolutions of yarn, permitting an adjustment to take place between the rolled support and the convolutions of yarn, inverting the package, and then applying equalizing radial pressure 20 within the core whereby the latter is given a uniform diameter and the yarn convolutions assume normal circumferences and are maintained substantially free of tangles during winding-off and other handling operations.

4. An apparatus for increasing the diameter of the thread free interior of wound yarn packages to permit the insertion of generally central supports therein comprising a base adjacent which a package having thread free interior is positioned, means extending beyond the base adapted to extend into the thread free interior of the package when it is in position against the base and means for expanding the extending 30 means for effecting the distension of the inner convolutions of yarn defining the thread free interior of the package, said extending means when expanded being constructed to receive a rolled support which engages the said inner convolutions whereby when the extending means is removed from the thread free interior of the package the support will be retained in the package by friction.

5. An apparatus for increasing the diameter of the thread free interior of wound yarn packages to permit the insertion of generally central supports therein comprising a base adjacent which a package having thread free interior is positioned, a plurality of radially movable fingers extending beyond the base adapted to extend into the thread free interior of the package when it is in position against the base and means for moving outwardly the extending fingers for effecting the distension of the inner convolutions of yarn defining the thread free interior of the package, said extending fingers when expanded being constructed to receive a rolled support which engages the said inner convolutions whereby when the extending means is removed from the thread free interior of the package the support will be retained in the package by friction.

6. An apparatus for increasing the diameter of the thread-free interior of wound yarn packages to permit the insertion of central supports therein comprising a base adjacent which a package having a thread free interior is positioned, a plurality 65 of radially movable upstanding fingers extending beyond the base adapted to extend into the thread-free interior of the package when it is in position against the base and means for moving the extending fingers for effecting the distension 70 of the inner convolutions of yarn defining the thread-free interior of the package, said extending fingers when expanded being constructed to receive a rolled support which engages the said inner convolutions whereby when the extending 75

fingers are removed from the thread-free interior of the package the support will be retained in the package by friction.

7. An apparatus for increasing the diameter of the thread-free interior of dried yarn packages comprising a base, a plurality of radially movable fingers extending beyond the base, means for

automatically radially extending the fingers until they are substantially parallel and means for retracting the fingers to an initial position such that they are out of parallel relationship and substantially closed at their apex.

PETER P. KRIEK.
